UNITED STATES PATENT OFFICE.

PETER E. BOYUM, OF WHALAN, MINNESOTA.

CAN-CART.

1,029,045.

Specification of Letters Patent. Patented June 11, 1912.

Application filed March 22, 1910. Serial No. 550,834.

To all whom it may concern:

Be it known that I, PETER E. BOYUM, a citizen of the United States, residing at Whalan, in the county of Fillmore, State of Minnesota, have invented certain new and useful Improvements in Can-Carts; and I do hereby declare the following to be a full, clear, and exact description of the invention, such as will enable others skilled in the art 10 to which it appertains to make and use the same.

This invention relates to improvements in can carts, of the class wherein provision is made for supporting one or more cans in 15 vertical position and to permit the same to be tilted when required for discharging their contents, and has for one of its objects to improve the construction and increase the efficiency and utility of devices of this character.

Another object of the invention is to improve the construction of the supporting frame and to limit the movement in one direction.

Another object of the invention is to provide a frame of improved construction and wherein means are provided for supporting the cans at different inclinations to correspond with the ground over which they are 30 moved.

Another object of the invention is to provide a device of this character wherein the cans may be "picked up" from the ground or deposited upon the ground by manipulating the supporting frame of the device.

With these and other objects in view, the invention consists in certain novel features of construction as hereinafter shown and described and then specifically pointed out in 40 the claim; and, in the drawings illustrative of the preferred embodiment of the invention, Figure 1 is a side elevation of the improved device with one of the carrier wheels detached and with the cans in elevated position, Fig. 2 is a plan view of the improved device with one of the cans in section on the line 2-2 of Fig. 1, Fig. 3 is a rear elevation of the improved device with the cans arranged as shown in Figs. 1 and 2, Fig. 4 is 45 a side elevation illustrating the manner of depositing the cans upon the ground and lifting them therefrom, Fig. 5 is an enlarged side elevation of one of the stub axles with its bracket, detached, Fig. 6 is a plan view, and Fig. 7 is an end elevation of the same.

The improved device comprises a main

frame substantially in U-shape and comprising a lower horizontal member 10 and vertical side members 11-12. At its upper end the member 11 is provided with a transverse bearing 13 while the member 12 is provided with a similar bearing 14. Rising from the lower member 10 of the frame is a standard 15, the standard having oppositely extending feet 16 bearing upon the member 10 and secured thereto by rivets or other suitable fastening means 17. The standard 15 is provided at its upper end with a bearing 18 similar to the bearings 13-14 and arranged in alignment therewith transversely of the 70 device. The bearings 13-14-18 are designed to support the cans, as hereinafter explained.

Secured to the vertical portions 11-12 of the frame is a U-shaped handle device comprising side members 19-20 and a transverse member 21, the latter forming the hand grip portion of the improved device. At their forward ends the side members 19-20 are downturned and secured by rivets or other suitable fastening devices to the vertical members 11-12. Each of the members 19-20 is provided with one of the downturned portions, but only one is shown for illustration and represented at 22. The member 19 is shown connected to the vertical member 11 by a diagonal brace 23 while the vertical member 12 is connected to the side member 20 by a similar diagonal brace represented at 24. By this means the frame 90 member 10-11-12 is rigidly connected to the handle member and supported therefrom and at right angles thereto, as shown. Connected to the side members 19-20 is a brace member 25 which bears at its lower 95 end on the ground, and supports the handle member normally in a horizontal position, as shown. All of the parts are formed of metal of suitable strength to withstand the strains to which they will be subjected. The handle member 19-20-21 is provided with a plurality of spaced apertures 26, the object to be hereinafter explained.

The improved device is shown arranged for two cans, and the cans are precisely alike and interchangeable, and the description of one will suffice for both. The cans are formed of galvanized iron or like material of suitable strength and comprise a body portion 27 and a detachable cover 28. Surrounding each can at its lower end is a metal band 28, and likewise surrounding each can

intermediate its ends is a similar band 29. The band 29 is preferably located a short distance from the center of the can so that a greater weight will be disposed below the intermediate band. Each of the bands 29 is provided with outwardly directed trunnions 30 to engage in the bearings 13—14—18, as shown.

One of the cans is disposed between the 10 vertical member 11 and the standard 15 with its trunnions engaged in the bearings 13—18, while the other can is located between the vertical member 12 and the standard 15 with its trunnions located in the bearings 14—18. 15 The bearing 18 will thus receive two of the trunnions and will be of sufficient length to receive them both, as shown in Fig. 2. By this means each of the cans is independently supported, and may be detached without 20 disturbing the other. The cans are thus suspended by their trunnions and will retain a vertical position no matter in what position the supporting frame may be disposed, because the greater bulk of the cans is located below the trunnions, as will be obvious.

Connected to the lower band 28 of each can is an eye 31 and connected to each eye is a holding rod 32, the holding rods having hooks 33 at their lower ends to engage the 30 eyes and with downwardly directed portions 34 at their other ends to engage in the apertures 26. By this means the cans may be rigidly supported relative to the frame when required, to prevent them from being accidentally displaced during the movements of 35 the device over the ground.

When traveling upon level ground the holding rods 33 will be connected in the apertures 26 which are located in position 40 to maintain the cans in parallel relations to the vertical members 11, but if the device is moving down a grade, the rods 33 will be adjusted to support the can at an angle to the longitudinal plane of the handle 19, 45 or in a vertical position regardless of the position of the frame, and by providing a plurality of the apertures 26 the cans may be maintained in vertical position regardless of the grade over which the device is 50 being moved. This is an important advantage, and adds materially to the utility and efficiency of the device.

Connected to the side members 11—12 rearwardly of the vertical members 11 are 55 stub axle members one of which is shown at 35 in Figs. 5, 6 and 7. Each of these members consists of an L-shaped plate forming a bracket 37, one arm of said plate being channelled longitudinally to form a seat in 60 which the side member of the frame is secured by bolts or other suitable fastening devices 38 while the other arm of the plate is provided with an integrally formed laterally directed stub axle. The stub axles provide means for supporting ground wheels 65

39—40, as shown. The ground wheels being located rearwardly of the vertical members 11—12, and likewise below the line of the bearings 13—14—18 provides an efficient means for not only supporting the cans above the ground, represented at 41, but likewise enables the cans to be deposited upon the ground by tilting the handle members 19—20 upwardly, as indicated in Fig. 4, or lifting the cans from the ground in the 75 same manner. This is an important advantage in the improved device and materially increases its efficiency and utility. The cans having independent supporting means may be independently disposed of and actuated, 80 as will be obvious.

The improved device is simple in construction, can be employed for handling cans in any manner desired, and may be constructed to hold any required number of the 85 cans, and it is not desired therefore to limit the improved device for cans of any required number or of any specific size. The cans may be employed for any required purpose, but is more particularly designed for 90 handling garbage and like material.

Another brace rod 41 is coupled at one end to the central standard 18 and at its other end to the handle member 21, as shown, to form a support for the standard. The 95 rods 32 may be employed as a means for tilting the cans by detaching them at their terminals 34, as will be obvious.

What is claimed is:—

The combination with a frame having vertically extending side arms and a cross bar connecting the lower ends of the side arms, the upper ends of said arms terminating each in a bearing, and wheels rotatably mounted at the side arms below the bearings 105 at the ends thereof, of a standard connected at its lower end to the central portion of the cross bar and having a bearing formed at its upper end, said standard being in alignment with the side arms of the frame, 110 a pair of receptacles, a band encircling each receptacle and provided with oppositely disposed trunnions, the outer trunnion of each band resting in the adjacent bearing of the side arm while the inner trunnions of both 115 bands rest in the bearing of the center arm, a U-shaped handle member having the ends 120 of the side arms thereof connected to the side members of the frame below the bearings thereof, brace rods extending diagonally between the arms of the handle member and the side arms of the frame, a brace member having two arms connected to the side arms of the handle member, said brace being adapted when the vehicle is at rest 125 to bear at its lower end against the ground, a holding rod coupled at one end to the upper end of the central standard between the receptacles and having a hook at its opposite end adapted to engage with the 130

handle member, and brace rods loosely connected at their lower ends to the bottom of the receptacle and provided with hooks at their upper end portions adapted to engage with apertures formed in the U-shaped handle member.

In testimony whereof, I affix my signature, in presence of two witnesses.

PETER E. BOYUM.
